UNITED STATES PATENT OFFICE.

JAMES BARRETT, OF BOSTON, MASSACHUSETTS.

STAND OR OVERFLOW PIPE FOR BATH-TUBS.

SPECIFICATION forming part of Letters Patent No. 443,310, dated December 23, 1890.

Application filed July 30, 1890. Serial No. 360,403. (No model.)

To all whom it may concern:

Be it known that I, JAMES BARRETT, of Boston, in the county of Suffolk and State of Massachusetts, have invented certain new and 5 useful Improvements in Stand or Overflow Pipes for Bath-Tubs, &c., of which the following is a specification.

This invention relates to overflow or stand pipes for bath-tubs or other like receptacles, in which a vertical tube is provided at its lower end with an annular valve adapted to fit a seat formed in the outlet fitting of the tub, said tube communicating with the interior of the tub at its upper end, so that 15 when water accumulates in the tub in a sufficient quantity to reach the upper end of the tube the surplus water will overflow through the tube, the tube being removable from the outlet fitting to permit the escape of the accumulation of water when it is desired to empty the tub.

My invention has for its object to provide improved means for supporting and guiding a stand or overflow pipe of this class and for 25 supporting it in a raised position when it is removed from the outlet-fitting.

The invention consists in the combination, with a stand-pipe having at its upper end an upwardly-projecting knob or handle provided 30 with vertical wings or ribs on its exterior, of a fixed arm attached to the end of the bath-tub or to any other suitable support and provided with a guide or socket at its outer end formed to receive the upper portion of the stand-pipe and the knob or handle attached thereto, said socket having an aperture in one side formed to permit the passage 35 of water from the interior of the tub into the upper end of the stand-pipe when the latter is in place in the outlet fitting of the tub, and notches or slots formed to receive the vertical wings or ribs on the knob or handle portion when the stand-pipe is in its operative 40 position with its lower end in the outlet fitting, the arrangement being such that the stand-pipe may be raised until its ribs or flanges emerge from the slots or notches in the said guide or socket, and then turned to cause the lower edge of said ribs to bear on 45 the upper edge of the socket, the stand-pipe

being thereby supported in a raised position, so that the water will escape from the tube through the outlet fitting.

The invention also consists in the combination, with the stand-pipe guiding and supporting arm, of a plate to which said arm is affixed and two faucets, also attached to said plate at opposite sides of the said arm, the said plate being attached to the end of the bath-tub and constituting a fixture which 55 supports the three parts—viz., the stand-pipe-supporting arm and the two faucets—so that said parts may be applied to the tub simultaneously, thus avoiding much of the labor incidental to the application of separate faucets in the usual way and giving the tub a 60 neater and more effective appearance than is possessed by a tub to which the faucets are attached separately in the ordinary way.

Of the accompanying drawings, forming a 70 part of this specification, Figure 1 represents a top view of a portion of one end of a bath-tub, showing my improved stand-pipe supporting and guiding devices and the faucet-supporting plate to which the same is attached. Fig. 2 represents a side view of the parts shown in Fig. 1 and a view of a portion of the end of the tub. Fig. 3 represents a section on line 3 3, Fig. 1. Fig. 4 represents a section on line 4 4, Fig. 1, looking toward the left, and showing the stand-pipe 75 raised from the outlet fitting and supported by the bearing of its lugs or ears on the upper end of the guiding-socket. Fig. 5 represents a section on line 5 5 of Fig. 4. Fig. 6 80 represents a section on line 6 6 of Fig. 3.

The same letters of reference indicate the same parts in all of the figures.

In the drawings, *a* represents a portion of the end of a bath-tub, and *b* the outlet fitting 90 of said tub, said part being of the usual or any suitable construction.

c represents the overflow or stand pipe, the lower end of which is formed as a valve *c'*, adapted to fit a seat made for it in the outlet 95 fitting.

d represents a knob or handle attached to the upper end of the stand-pipe *c*, preferably by means of a stem *d'*, attached to or formed on the handle *d* and screw-threaded at its 100

lower end for engagement with a cross-bar or yoke *e*, attached to the upper end of the stand-pipe *c*. On the handle *d* are formed two vertical ribs or wings *ff*, (shown in Figs. 4 and 5,) said ribs or wings being formed on a cylindrical flange extending downwardly from the main portion or body of the handle *d*.

g represents an arm rigidly attached to the end of the tub *a* in any suitable manner and provided at its outer end with a spherical enlargement or socket *g'*, which has openings in its upper and lower portions to receive and permit the vertical movement of the stand-pipe *c* and the flange portion of the handle *d*, said pipe and handle being freely movable vertically in said socket *g'*.

h represents a slot or port formed in the rear portion of the socket *g'* for the reception of water from the tub, said port permitting the water to enter the interior of the socket *g'* and flow from thence downwardly through the stand-pipe *c*, the upper end of said stand-pipe being open within the socket *g'*. It will be seen, therefore, that when the water rises in the tub to the height of the port *h* it will overflow through said port and the stand-pipe.

In the upper edge of the socket *g'* are formed two notches or slots *ii*, which are formed to receive the wings *ff* when the handle *d* and stand-pipe *c* are turned to position to cause said ribs to coincide with the slots *ii*. When the ribs or wings *ff* enter the slots *ii*, the stand-pipe is not supported by the arm *g* and its socket, and the valve portion *c'* of the stand-pipe bears on its seat in the outlet fitting, as shown in Fig. 3. When it is desired to empty the tub, the handle and stand-pipe are raised until the ribs or wings *ff* emerge from the slots *ii*, when by partial rotary movement of the handle the said ribs or wings are thrown out of line with the slots *ii* and caused to bear on the upper edge of the socket *g'*, as shown in Fig. 4, so that the handle and stand-pipe are supported in an elevated position by said socket.

It will be seen that the arm *g*, affixed to the tub and having the spherical enlargement provided with the port *h*, constitutes a neat and substantial guide and holder for the stand-pipe and keeps the stand-pipe always in place in the bath-tub so that it cannot be removed.

I prefer to secure the arm *g* to the end of the tub by means of a plate *k*, to which the arm is secured in any suitable way. Said plate is elongated horizontally, as shown in Figs. 1 and 2, and to it are attached at opposite sides of the arm *g* two faucets *m m*, which may be of any suitable construction, and are rigidly attached to the plate *k* in any suitable way. The casings of the faucets are provided with tubular shanks *m'*, which extend through the wall of the tub, and are secured by nuts *o*, screwed upon their threaded ends outside of the tub, said nuts being turned up against the exte-

rior of the tub or against the casing thereof and serving to secure the plate *k* in place. It will be seen, therefore, that the plate *k* supports the stand-pipe, holding and guiding arm *g* and the faucets *m m*, so that all three can be applied and removed together, and no soldering or independent attaching of either part is required. The plate *k* may be of any ornamental shape desired and imparts a very desirable finish to the end of the bath-tub.

To enable the stand-pipe and its valve to be supported by the end of the tub at any desired distance therefrom, and thereby adapt said stand-pipe and valve to different makes of tubs, (the waste-outlet being farther from the end of the tub in some tubs than in others,) I provide a telescopic connection between the guiding-socket *g'* and the end of the tub. Said telescopic connection comprises the arm *g* and a socket *g''*, attached to the plate *k*, or, if preferred, directly to the end of the tub, said socket receiving the arm *g* and permitting the latter to slide lengthwise to increase or decrease the distance between the guiding-socket *g'* and the end of the tub. A setscrew *g'''* in the socket *g''* holds the arm *g* at any point to which it may be adjusted. It will be seen that the socket *g''* and arm *g*, with its guiding-socket *g'*, constitute a telescopic bracket or guide, which may be readily shortened or lengthened, as occasion may require. I do not limit myself, however, to the use of the telescopic construction; but may make said arm or bracket non-adjustable without departing from the spirit of my invention.

I claim as my invention—

1. The herein-described improved overflow for bath-tubs, comprising the fixed arm having an outer socket or spherical enlargement provided with a port or opening in one side, the stand-pipe having a valve at its lower end and designed to move at its upper end in said socket or enlargement, and the handle secured to the upper open end of said pipe and designed to be supported by said socket or enlargement, substantially as set forth, whereby when said pipe is lowered and its valve seated the upper end thereof is coincident with said port or opening, as stated.

2. The herein-described improved overflow for bath-tubs, comprising the fixed arm having an outer socket or spherical enlargement provided with a port or opening in one side and with opposite slots in its upper edge, the stand-pipe having a valve at its lower end and designed to move at its upper end in said socket or enlargement, and the handle secured to the upper open end of said pipe and having ribs or wings designed to fit in said slots, substantially as set forth, the upper open end of said pipe being coincident with said port or opening when said pipe and its valve are lowered, as stated.

3. The combination of the stand-pipe guiding and holding arm *g*, the plate *k*, to which said arm is rigidly attached, and the faucets *m m*, attached to said plate and provided

with screw-threaded shanks $m' m'$ and the
clamping-nuts $o o$, whereby said plate, together
with the stand-pipe-supporting arm and the
faucets, may be secured to a bath-tub or other
5 like receptacle, as set forth.

In testimony whereof I have signed my
name to this specification, in the presence of

two subscribing witnesses, this 19th day of
July, A. D. 1890.

JAMES BARRETT.
